UNITED STATES PATENT OFFICE.

DAVID F. RANNEY, OF NORTHAMPTON, MASSACHUSETTS.

MACHINE FOR SHARPENING PENCILS.

SPECIFICATION forming part of Letters Patent No. 340,818, dated April 27, 1886.

Application filed November 9, 1885. Serial No. 182,177. (No model.)

To all whom it may concern:

Be it known that I, DAVID F. RANNEY, a citizen of the United States, residing at Northampton, in the county of Hampshire and State of Massachusetts, have invented new and useful Improvements in Machines for Sharpening Pencils, of which the following is a specification.

This invention relates to improvements in pencil-sharpening machines, the object being to provide improved shaving or cutting and point-grinding devices upon a single rotating shaft, combined with improved means for holding a pencil at a suitable angle to the face 10 of the grinding-wheel, whereby a properly-formed point is made, said holding devices being adjustable to hold pencils at varying angles.

In the drawings forming part of this specification, Figure 1 is a perspective view of a pencil-sharpening machine constructed according to my invention, a part of the table and of the frame supporting the latter being broken away. Fig. 2 is a perspective view of 20 the pencil-holding devices, showing a part of the hollow shank of the holder and the coiled spring in section, and a portion of the stand on which said holder is supported, the top thereof being broken away to show said shank and spring, this figure also illustrating the manner in which a pencil is engaged and held 25 by the holder. Fig. 3 is a side view of the pencil-holder yoke in modified form, with its shank partly broken off, and of a portion of its supporting-stand.

In the drawings, A is a table having suitable legs and supporting frame-work, and in the latter, in suitable bearings, is hung the crank-shaft B, to which a rotary motion is 30 given by the foot-treadle F, which is connected with the shaft B by the pitman E, in the usual way. A driving-pulley, D, is fixed on shaft B, having a groove in its periphery in which the driving-belt h runs. A standard, K, is 35 fixed in an upright position on the table A, having in its upper end a suitable bearing or bearings in which the shaft a rotates, driven by said belt h, which runs over a grooved pulley, e, which is fixed on said shaft. One 40 end of shaft a is perforated longitudinally and one side of the perforated part of the shaft

is slotted, as shown in Fig. 1, and at one side of said slot the knife c is secured, making the well-known hollow cutter for shaving by rotary movement the ends of lead-pencils, giving 55 the usual conical form to the ends of the wooden portion of the latter, it being understood that the said perforation in the end of shaft a is of conical form, and that knife c is set on a line with the side of the perforation. 60 A grinding-wheel, m, is secured on the end of shaft a, opposite to that in which is said hollow cutter, said grinding-wheel being preferably the well-known "emery-wheel," and a balance-wheel, d, is fixed on said shaft to 65 assist in giving steadiness to its rotary motion.

The pencil-holding devices are located on the table A, opposite the periphery of the grinding-wheel, and are constructed and arranged as follows: A standard, n, is secured 70 on table A by screws, as shown, one of the latter passing through the curved slot o in the foot of said standard, thereby providing for swinging the standard and securing it in different positions on the table. The upper end 75 of standard n is provided with a cylindrical perforation in a plane with the top of table A, and a set-screw, x, passes through the side of said perforation. A pencil-holder yoke, f, consisting of two arms, 3, united by a cross-piece at right angles to the latter, has a hollow shank, z, projecting rearward from said cross-piece, and a perforation is made through 80 the latter and that portion of the shank directly adjoining it leading into the hollow 85 portion at its rear end, said shank z being of proper external diameter to fit into said cylindrical perforation in the standard n, whereby the yoke f is supported thereon, and is permitted to be rocked more or less and moved 90 back and forth opposite wheel m; and when moved or adjusted to a desired position the yoke is there secured by the set-screw x, whose point enters a groove made in the side of shank z. (Shown in Fig. 1.) Each arm 3 is 95 provided with a notch, 2, in its end.

The pencil-holder y is a hollow metallic piece, of the form shown, fitting loosely between the arms 3 of the yoke, and having a stem, t, thereon extending rearwardly through said 100 perforation in the cross-piece of the yoke and through the shank z, a head, J, being secured

to the end of the stem, a coiled spring, *w*, being placed on stem *t*, between said head and the inner end of the socket in the shank *z*, whereby the pencil-holder is drawn backward 5 between the arms 3 of the bifurcated yoke *f*.

If desired, the arms 3 of the yoke may be made as shown in Fig. 3—that is to say, without the notches 2 in the ends thereof; but in place of the latter, having holes 5 through each 10 arm, opposite each other, through which to pass the pencil, so that it may be held by the holder *y*, substantially as shown in Fig. 2.

The operation of the above-described machine is as follows: Through the treadle *F* and 15 driving-wheel *D* rapid rotary motion is given to shaft *a*. In order to quickly reduce the end of a pencil to a conical form approximating that which it will have finally, the operator first forces said pencil end into the hollow end 20 of shaft *a*, thus submitting it to the action of the knife *c*, whereby much of the surplus wood is removed without cutting the graphite center, said knife not being adapted to properly treat the latter. The operator then presses against 25 the head *J* on the stem of holder *y*, forcing the end of the latter beyond the ends of the arms 3 far enough to allow of passing the pencil *s* through holder *y* and in front of the ends of 30 said arms. The stem of the holder is then released, and the spring *w*, which was compressed when the holder was moved outward, draws the latter backward, forcing the pencil against the notched ends of arms 3 in the position shown, but not so tightly but 35 that it can be slowly rotated while so held.

The standard *n*, in which the holder and the yoke *f* are supported, is set in such a position on table *A* as to hold the pencil placed in the holder at an incline to the side of the wheel proportionate to the shape of the sharpened end of 40 the pencil to be produced, said position of the standard being fairly represented in Fig. 1, but being capable of adjustment in either direction by means of the curved slot *o* and the screw 45 passing through it. To accommodate the holder to pencils of larger or small diameters, the yoke *f* is made adjustable in the direction of the length of the shank *z* by moving the latter in the standard *n* and securing it by the set- 50 screw *x*. Thus it is seen that with the holder

and yoke in the position relative to the outer side of wheel *m*, indicated in Fig. 1, the pencil, when placed between the holder and the ends of arms 3, as shown, and pressed forward and rotated, has its side near its end forced against 55 the wheel, (the latter being rotated in the direction shown by the arrow,) and thereby a conical form is given to the end thereof, and the graphite is ground to a smooth and perfect point, and the adjoining wood is of a like smooth 60 finish, and with said point is concentric with the surface of the pencil.

It is not essential that the end of the pencil be partially reduced to a conical form by the use of said hollow cutter before it is ground on 65 wheel *m*; but by the use of said cutter the pencil is more quickly pointed.

Pencils of slate are quickly pointed on this machine, by holding and rotating them as above described while pressing them against the outer side of wheel *m*.

The pencil, it will be seen, is held or drawn toward the grinding-wheel by the force of the spring *w*, which is sufficient to hold it against the wheel, and if it be pressed forward unduly 75 the spring yields and prevents the point of the pencil from breaking.

What I claim as my invention is—

A machine for pointing pencils, consisting of a rotating shaft having a grinding-wheel, substantially as described, secured thereon, combined with pencil-holding devices supported on a suitable standard near said wheel, consisting of a bifurcated yoke having notches in the ends of its arms and a hollow shank by 80 which said yoke is secured to said standard, a hollow holder located between said arms and capable of a horizontal motion therebetween, and having a stem extending through the hollow shank of the yoke, and having a head on 85 its end, a coiled spring on said stem between said head and the inner end of the cavity in said yoke-shank, and means, substantially as described, for imparting a rotary motion to said shaft, substantially as set forth.

DAVID F. RANNEY.
